George J. Evans

UNITED STATES PATENT OFFICE

HERMAN H. COOK, OF PENDER, NEBRASKA

MAIL BOX

Application filed October 28, 1929. Serial No. 402,970.

This invention relates to mail boxes of the rural delivery type and which embodies among other characteristics means whereby the box may be opened and closed through contact with an appropriate portion of the carrier's vehicle.

Another object of the invention embodies an operating lever for this purpose.

An additional object of the invention consists of a door operating means having connection with the lever.

More specifically stated the operating lever has a portion of its length disposed in juxtaposition to a contact member included upon the carrier's vehicle.

With the above and other objects in view, the invention further consists of the following novel features and details of construction, to be hereinafter more fully described, illustrated in the accompanying drawing and pointed out in the appended claims.

In the drawing:—

Figure 1 is a perspective view of my invention as applied upon a form of mail box.

Figure 2 is a side elevation of the invention as applied and illustrating by full and dotted lines the relative positions of the door and operating means for the box.

Figure 3 is a rear end elevation of the box showing the operating means and door actuating means in active and inactive positions.

Figure 4 is a section on the line 4—4 of Figure 2.

Referring to the drawings in detail where-in like characters of reference denote corresponding parts, the reference character 10 indicates a conventional form of mail box supported upon a standard or post 11. The forward or entrance end of the box is inclined in the manner shown in Figure 2 of the drawing to accommodate a door or closure 12. The latter is provided with a flange portion 13 rearwardly projecting from the upper curved portion and parallel sides thereof for overlapping superimposed relation with the adjacent portions of the mail box. The lower edge of the door or closure is not flanged whereby the door when swung from the dotted to the full line positions shown in Figure 2 of the drawing will ef-

fectively close the entrance end of the mail box.

A hanger or fulcrum bar 14 of elongated U-shape formation is eccentrically pivoted or mounted, as at 15, upon opposite sides of the mail box adjacent the rearmost end thereof whereby the closure or door 12 will have a normal tendency to remain in closed position. The fulcrum bar is furthermore provided with pivot pins 16 eccentrically connected with diametrically opposed portions of the flange 13 for the closure or door 12 adjacent the lowermost edge of the latter to permit rocking movement of the door and to overcome any possibility of jamming or binding. Excessive swinging motion of the door upon the fulcrum bar, incident to its eccentric pivotal connections therewith, is restricted by the inwardly offset portions 17 upon the outermost projecting ends of the fulcrum bar and which engage the outer surface of the door or closure 12. The operating bar as mentioned in the foregoing and as indicated at 18 is disposed for the major portion of its length beneath the corrugated bottom of the mail box and rockingly mounted within the eyes or loops of screw eyes or other forms of bearing members 19. Stop collars 20, carried at intervals upon the operating lever, are engageable with the outer sides of the respective bearing members to prevent undue longitudinal shifting motion of the operating lever therethrough. The innermost end of the operating lever is offset to provide a horizontal portion 21 having connection with the yoke portion of the U-shaped fulcrum bar 14 through the instrumentality of a chain connection 22. A vertical leg 23 offset and depending from the forward end of the operating lever 18 is disposed in the path of movement of a pin or projection 24 to be arranged upon the running board or other appropriate portion of the mail carrier's mode of transportation.

The vehicle is run near the mail box to effect engagement of the pin or projection 24 with the vertical leg 23 of the operating lever 18 to impart rotation to the latter and to dispose the horizontal portion 21 at a downward inclination whereby the chain connection 22

following therewith will cause the fulcrum bar 14 to occupy the dotted line Figure 2 position and hold the closure or door 12 in such position until the carrier moves on toward the next mail box. It is not necessary 5 that the carrier retract his vehicle to release the pin or projection 24 from the vertical leg 23 of the operating lever 18 to release the door or closure 12 in view of the fact that 10 the horizontal portion 21 of the operating lever 18 does occupy a true vertical position when the door or closure 12 is in a fully open position. For this reason, the vehicle can continue on and the door or closure 12 will 15 be elevated still higher as the pin or projection 24 slides against and elevates the vertical leg 23 at a correspondingly radical inclination.

The invention is susceptible of various 20 changes in its form, proportions and minor details of construction, and the right is herein reserved to make such changes as properly fall within the scope of the appended claims.

Having described the invention, what is 25 claimed is:

1. A mail box and operating means there-
for comprising a fulcrum bar of U-shape
formation having eccentric pivotal connec-
tion with the box, a closure lid obliquely in-
30 clined upon the entrance end of the box and
having pivotal connection with the adjacent
portions of the fulcrum bar, a flange carried
by and inwardly directed from the lid de-
signed for overlapping engagement with the
35 box, an operating lever journaled beneath
the box having an end horizontally offset
from one end in parallelism to the yoke por-
tion of the fulcrum bar, a chain connection
between the yoke portion of the fulcrum bar
40 and of the horizontally disposed end oper-
ating lever, and a leg depending from the oppo-
site end of the operating lever.

2. A mail box and operating means there-
for comprising a fulcrum bar of U-shape
45 formation partially surrounding the box and
pivotally mounted eccentrically therewith, a
closure lid obliquely disposed upon the en-
trance end of the box having pivotal eccentric
connection with the adjacent portions of the
50 bar, the ends of said bar being inwardly off-
set over the front of the closure lid to re-
strict inward swinging movement thereof
from the adjacent pivotal connections there-
with, an operating lever journaled beneath
55 the mail box terminating at one end in a
horizontal offset portion disposed in par-
allelism with the yoke portion of the fulcrum
bar, a chain connection established between
the yoke portion of the bar and horizontally
60 offset extremity of the operating lever, and
a leg vertically disposed upon the forward
end of the operating lever.

In testimony whereof I affix my signature.
HERMAN H. COOK.
